Primary Examiner — Cynthia Ramirez(74) *Attorney, Agent, or Firm* — Brian Roffe(57) **CLAIM**

The ornamental design for a bag-retaining insert for waste container, as shown and described.

DESCRIPTION

FIG. 1 is a perspective view of a bag-retaining insert for waste container showing my new design;

FIG. 2 is a bottom perspective view;

FIG. 3 is a top view thereof;

FIG. 4 is a front view thereof;

FIG. 5 is a rear view thereof;

FIG. 6 is a left view thereof;

FIG. 7 is a right view thereof; and,

FIG. 8 is a bottom view thereof.
